FRANK E. ANDERSON, OF EAST ORANGE, NEW JERSEY.

SCOURING AND WASHING APPARATUS.

SPECIFICATION forming part of Letters Patent No. 430,817, dated June 24, 1890.

Application filed February 13, 1890. Serial No. 340,348. (No model.)

To all whom it may concern:

Be it known that I, FRANK E. ANDERSON, of East Orange, in the county of Essex and State of New Jersey, have invented a new and useful Improvement in Scouring and Washing Apparatus, of which the following is a full, clear, and exact description.

This invention relates to apparatus for scouring, washing, or dyeing various fibrous materials. It is more particularly intended, however, for the cleansing and washing of wool, and is more especially designed as an improvement upon the invention patented by Samuel Hodgson, September 3, 1889, No. 410,519, for a scouring and washing machine, in which the main objects of the invention were to provide for a uniform submersion of all of the wool or other fiber operated upon, and to provide for a submersion of any length of time. Said machine, which included a process subsequently patented to said Hodgson, January 14, 1890, No. 419,331, operated upon the principle of submerging the staple and subjecting said staple and its surrounding liquid to forward intermittent impulses, and in carrying out this process the machine patented September 3, 1889, as above named, consisted, essentially, of a normally-filled tube or conduit and a flushing mechanism arranged in connection therewith. These and other details included in said machine are used in this my improvement, which, however, has other features in addition, including a succession or series of fiber-submerging tubes, one following the other, and the one which follows up the work of the preceding one either having a continuous or intermittent flow of liquid through it; but the same will here be described as having continuous flow through it instead of operating by forward impulses; also, pressure or squeeze rolls interposed between the tubes and at the terminus of the series, whereby the wool or fiber under treatment is more effectually cleaned, substantially as hereinafter described.

Reference is to be had to the accompanying drawings, forming a part of this specification, in which similar letters of reference indicate corresponding parts in all the figures.

Figure 1 is a plan view of my improved scouring and washing apparatus. Fig. 2 is

a vertical longitudinal section of the same, taken upon the line *x x* in Fig. 1; and Figs. 3, 4, and 5 are vertical transverse sections, 55 upon a larger scale, taken, respectively, upon the lines *w w*, *y y*, and *z z* in Fig. 2.

A is the first of a series of tubes or flumes, of which there may be any number in succession, one in advance of the other, although 60 only two are here shown, (marked A B.) At the one end of this tube A is a hopper C, into which the wool or fiber to be treated is first fed by any suitable means, while the other end of said tube is raised, so that the lower 65 edge of the discharge-opening *a* will be above the level of the top of the main body of the tube.

On top of the hopper C is a tank D, that supplies by overflow the scouring or washing 70 liquid to the flume A and keeps such flume, tube, or conduit normally filled with the liquid. Applied to said hopper C is a tilting flushing-bucket E, into which the liquid from the tank D flows. This tilting flushing- 75 bucket as it tilts serves to give the necessary intermittent forward impulses to the wool or fiber and its surrounding liquid in and through the flume or tube A.

At the discharge end *a* of the tube A, over 80 or within a drip-pan F, is an endless traveling cloth or other, preferably porous, apron G, which serves to carry the wet wool or fiber forward to and between a pair of pressure or staple squeezing-rolls H H in and over the 85 drip-pan F. These rolls or one of them is made adjustable to give any degree of pressure required—as, for instance, by screws applied to the bearings of the upper roll. Beyond these rolls H H is another endless 90 traveling belt or apron G', set inclining upward within a channel-way I, and serving to deliver the partially-cleansed wool or fiber into a second hopper J, mounted on the one end of the second flume or tube B, the wool 95 being delivered above the level of the fall of liquid therein, which is supplied from an overflow-chamber b. The liquid squeezed out of the wool or fiber by the pressure-rolls H H is returned from the drip-pan F back to a tank 100 K, from whence it is returned or supplied by a pump or steam-pulsometer L and suitable connections to the overflow-tank D. The endless traveling aprons G G' and the squeeze or

pressure rolls H H are positively driven by any suitable arrangement of gearing, an ordinary system for the purpose being shown in Fig. 1. The tube or flume B also has the lower edge of its discharge-opening a' at the one end of said tube at the level of the top of the main body of the tube; but the flow of liquid and passage of the fiber through this tube, instead of being by intermittent impulses as well as continuous, as in the tube or flume A, is continuous only, the liquid being continuously supplied by the overflow-chamber b without the intervention of a tilting flushing-bucket.

From the tube B the wet wool in being discharged slides down an incline d and pushes any wool or fiber ahead of it up to and between another pair of adjustable squeeze or pressure rollers H' H', suitably boxed in at their sides and back to insure the passing water or liquid being run out to said rolls together with the wool or fiber. A rotating fan-like device e at the back of these rolls serves to regulate the delivery of the wool or fiber. Beneath the rolls H' H' is a drip-pan N, which serves, by a suitable pipe-connection, to pass the liquid flowing out of the tube B and squeezed from the wool while passing between said rolls back to a tank K, from whence it may be returned by a pulsometer or pump O to the overflow-chamber b. The pressure-rolls, or one of them H H', are also positively driven, as likewise the fan-like device e, by any suitable gearing—such, for instance, as shown in Fig. 1.

Of course for cleansing wool the liquid used may be suitably heated, as customary in such cases.

By the use of a series of successive flushing-flumes, the contents of which are subjected to intermittent impulses and a continuous current, and the employment of squeeze or pressure rolls between the flumes and at the end of the series, where any desired pressure may be given, not only will the wool, supposing that to be the material being treated, be properly submerged and soaked and rinsed without jamming or injury to its fibers; but the wool, in passing between the squeeze-rolls, will receive a greater proportion of cleansing in the squeezing operation than in the soaking one, the hard pressure of the rolls forcing the liquid through every part of the wool, besides separating the dirt and grease, which has been loosened and softened by the soaking operation.

It should be observed that the flushing flumes or tubes may either be subjected to an intermittent or continuous current through any or all of them. Means for doing both are here shown. This remark applies whether the apparatus has only one flushing-flume or a series of flushing flumes or tubes in succession, so long as squeeze-rolls be combined either with the one flume or with the series of flumes. Again, by the term "flushing flume or tube" is meant a tube or flume the liquid

or contents in which will not discharge at the outlet without raising the level of the liquid to flush said tube and fill it for more or less of its length, both in direction of its height and width, no matter whether said flume or tube be horizontal and made with an upturned delivery end or not, and regardless of its shape, it only being necessary that the level of the liquid-line when normal should at some point, and preferably throughout the full length of the tube, close the tube diametrically, so as to give the requisite resistance and friction. This may be done by making the outlet portion of the tube, though not necessarily its extremity, elevated in relation to the body of the tube.

It should here be observed that the flushing flumes or tubes in which the scouring and washing is done essentially differ from mere upright tanks or receptacles provided with toothed drums or other special rotating devices for agitating and working the wool while within said receptacles, and with pumps for passing the wool from one receptacle to another or into a raking device, and further provided with pressure rolls or wringers and endless-belt conveyors for conveying the wool or staple through and delivering it from the apparatus. Each scouring and washing flume or tube in my invention is not dependent upon interior operating devices or pumps for lifting the wool, but it is simply a fiber-submerging tube, normally filled with fluid, having its opposite end portions so arranged that a current by gravitation passes through the tube, and the latter is kept filled for a portion at least of its length with liquid, so as to give the requisite resistance and friction and to provide for a proper and uniform submersion of all the wool or fiber passing through the tube. Wool or other staple thus scoured or washed is in a condition to be acted upon more thoroughly and perfectly by squeeze or pressure rollers without injury to the fiber, and where a series of such flushing flumes or tubes and a series of such pressure-rollers outside of the delivery end of each flushing flume or tube, respectively, are used the efficiency of the apparatus is greatly enhanced.

Having thus described my invention, I claim as new and desire to secure by Letters Patent—

1. In apparatus for scouring and washing wool or other fibrous material or staple, the combination, with a flushing flume or tube—that is, a tube normally filled with liquid and having an elevated outlet and means for supplying liquid thereto—of pressure or staple squeezing rolls arranged beyond the outlet end of said flume, essentially as herein set forth.

2. The combination, with a series of flushing flumes or tubes having elevated outlets and arranged one in advance of the other, a means for delivering an intermittent supply of liquid to one of said tubes, and a means

for delivering a continuous supply of liquid to the succeeding tube, of pressure or staple squeezing rolls arranged in relation to the tubes or flumes, as and for the purpose stated.

5 3. The combination, with a series of flushing flumes or tubes having elevated outlets and arranged one in advance of the other, hoppers at their inlet ends, and means for supplying, respectively, said tubes with liquid, 10 of pressure or staple squeezing rolls arranged between said tubes and at the end of the

series of tubes, conveying devices for conveying the staple to and from the pressure-rolls between the tubes, and a guide or incline for passing the staple from the last of said 15 tubes to the pressure-rolls at the end of the series of tubes, as and for the purpose stated.

FRANK E. ANDERSON.
